W. S. Vedder
TROY, N.Y.

Cut 220

UNITED STATES PATENT OFFICE.

OTIS G. CLARK, OF TROY, AND DANIEL D. BUCKLIN, OF LANSINGBURG,
EXECUTORS OF NICHOLAS S. VEDDER, DECEASED, AND TOBIAS S.
HEISTER, OF LANSINGBURG, NEW YORK; SAID HEISTER ASSIGNOR
TO SAID CLARK AND BUCKLIN AS EXECUTORS.

DESIGN FOR A BASE-BURNING STOVE.

SPECIFICATION forming part of Design No. 11,884, dated July 20, 1880.

Application filed June 14, 1880. Term of patent 3½ years.

To all whom it may concern:

Be it known that NICHOLAS S. VEDDER, deceased, late of the city of Troy, in the county of Rensselaer and State of New York, and 5 TOBIAS S. HEISTER, of the village of Lansingburg, in said county and State, did, in the lifetime of said NICHOLAS S. VEDDER, jointly invent and produce a new and original Design 10 for Base Burning Stoves; and that OTIS G. CLARK, a resident of the city of Troy, aforesaid, and DANIEL D. BUCKLIN, a resident of the aforesaid village of Lansingburg, are the executors of the last will and testament of said NICHOLAS S. VEDDER, deceased; and we, 15 the said OTIS G. CLARK, DANIEL D. BUCKLIN, and TOBIAS S. HEISTER, hereby declare that the following is a specification of the said new design, reference being had to the accompanying cut, print, or engraving.

20 One feature of this invention is the design for the legs A, composed of the upper panel portion, b, having the row of pointed arches b', covering the heart-shaped ornaments b'', the swelling middle portion, c, having the moldings c' and ornament c'', and the concavely-contracted lower portion, d, having the ornaments d', all shaped and arranged substantially as shown in the aforesaid print.

25 Another feature is the design for the base-plate B, the same being composed of the smooth surface inclined outer rim having the long flat faces e, alternating with the shorter flat faces e', and the intervening concavely-curved faces e'', the adjoining inner and more 30 lowly-inclined rim portion composed of the long parts f, alternating with the shorter parts f', each having the matted surfaces f'', and ornamental edging f'', and the intervening ornated concavely-curved parts f'', the 35 plane surface g, and the inner molded portion having the angular projections h, with concavely-curved sides, and the convexly-curved intervening parts h', all shaped and arranged together as shown in the aforesaid cut.

40 45 Another feature is the design for the foot-rail C, composed of the smooth flat top and inclined sides, having the long straight por-

tions i, alternating with and inclined obtusely to the shorter straight portions i', and the intervening parts i'', curved concavely outward 50 and convexly inward, all substantially as represented in the accompanying engraving.

Another part is the design for the ash-pit section D, composed of the ornamented panel J, ornamental open-work j, and the panel-plates 55 k, vertically concave and horizontally convex, and having the ornament l and ornamented fillets l' on the middle portion, and the compound border, composed of the outer row of flute 60 ornamentations, m, inner ornamented fillet, m', with rectangular drop-ornamented inwardly-projecting parts m'', intermediate matted ground, and star-like corner ornaments, m'', all shaped, arranged, and combined as shown in the aforesaid cut.

Another part is the design for the fire-pot section E, composed of the ornamented rear side panel, N, lower vertical portion, O, having the incut ornamentations n, and the inclined doors P, each having the two horizontally-70 oblong illumination-apertures o, with truncate corners, and the surrounding frame having the matted ground o' and fillet ornamentations o'', all shaped and arranged together so as to appear as represented in the aforesaid print.

Another part is the design for the combustion-chamber section F, composed of the ornamented rear side panel, Q, and the doors R, having the three upper and two lower illumination-apertures p, with truncate corners, the 80 series of angular ornaments p' along the top, and the frame-work having the matted ground p'', and the varied fillet ornamentations p'', all shaped and arranged so as to appear as represented in the aforesaid engraving.

Another feature is the design for the panel ornaments G of the upper section, the same being composed of the central figure, representing a rearing horse, q, having a mailed rider, r, thereon displayed on the picturesque background s, inclosed by the ornamented base part s', columns s'', and arched top s'', all shaped and disposed so as to appear as represented in the aforesaid cut.

Another feature is the design for the borders of the panels of the upper section, II, the same consisting of the top and bottom borders, composed of the series of outer ornamentations, 5 t , inner ornamentation, t' , and intervening ground t^2 , and the columns between the panels, having the angularly-ornamented base u , ornamenteinly inct shaft u' , and scroll leaf ornamented capital u^2 , all shaped and arranged as 10 represented in the aforesaid engraving.

Another feature is the design for the ornamental top rim, I, composed of the smooth polished face-surface v , the series of alternate angular depressions and projections v' along the 15 lower edge, and the series of narrower and more numerous alternate rounded depressions and projections v^2 along the upper edge, and all shaped, arranged, and proportioned as represented in the aforesaid print.

20 Another part is the design for the urn U, composed of the outer semicircular lower part, w , supporting the broader part w' , covered by the toothed band w^2 , heart-shaped ornament w^3 , side brackets, $x x$, top ornamented arch, y , 25 inner serrate-edged arch, z , and intermediate part z' , all shaped, ornamented, and arranged together as shown in the aforesaid cut.

What is claimed as the joint invention of the aforesaid NICHOLAS S. VEDDER and TOBIAS 30 S. HEISTER is—

1. The design for the legs A, composed of the parts $b b' b^2$, $c c' c^2$, and $d d'$, all shaped and combined as shown and described.
2. The design for the base-plate B, consisting 35 of the parts $e e' e^2$, $f f' f^2 f^3 f^4$, g , and $h h'$, all shaped and combined as set forth.
3. The design for the foot-rail C, composed

of the parts i , i' , and i^2 , all shaped, proportioned, and arranged as shown and described.

4. The design for the ash-pit section D, composed of the parts $J j k l l' m m' m^2 m^3$, all shaped and arranged as set forth. 40

5. The design for the fire-pot section E, composed of the parts N , $O n$, $P o o' o^2$, all shaped and arranged together as shown and specified. 45

6. The design for the combustion-chamber section F, consisting of the parts Q , $R p p' p^2 p^3$, all shaped and arranged as set forth.

7. The design for the panel ornaments G for the upper section, composed of the parts $q r s s' s^2 s^3$, all shaped and combined as set forth. 50

8. The design for the border of the panels of the upper section, II, consisting of the parts $t t' t^2$ and $u u' u^2$, all shaped and arranged together as shown and described. 55

9. The design for the top rim, I, composed of the parts $v v'$, and v^2 , all shaped, proportioned, and combined as shown and specified.

10. The design for the urn U, consisting of 60 the parts w , w' , w^2 , w^3 , $x x$, y , z , and z' , all shaped and arranged together as shown and described.

In testimony whereof we hereunto set our hands, in the presence of two subscribing witnesses, this 10th day of June, 1880. 65

OTIS G. CLARK,
DANIEL D. BUCKLIN,
Executors of Nicholas S. Vedder, deceased.
TOBIAS S. HEISTER.
